UNITED STATES PATENT OFFICE.

CHARLES W. WILSON, OF BEREAL, OHIO, ASSIGNEE, BY DIRECT AND MESNE ASSIGNMENTS, OF SIX FORTY-EIGHTHS TO WILLIAM K. EVANS, SIXTEEN FORTY-EIGHTHS TO SAMUEL CHEGWYN, AND TWENTY-SIX FORTY-EIGHTHS TO MARY E. EVANS, ALL OF BEREAL, OHIO.

AUTOMATIC TRAIN CONTROL.

1,304,642.

Specification of Letters Patent.

Patented May 27, 1919.

Application filed June 27, 1916. Serial No. 106,129.

To all whom it may concern:

Be it known that I, CHARLES W. WILSON, a citizen of the United States, residing at Bereal, in the county of Cuyahoga and State of Ohio, have invented certain new and useful Improvements in Automatic Train Controls, of which the following is a specification.

In the operation of railway trains many accidents are traceable to neglect on the part of the engineer or other train operator to observe and give heed to danger signals, hence a necessity has arisen for automatic train stop mechanism which acts independently of the engineer or operator to apply the brakes in an emergency and bring the train to a standstill.

The present invention relates to mechanism of the character aforesaid and embodies two coöperating parts, one of such parts being mounted upon the train and having connection with the air-brake system to apply the brakes, and the other one of such parts being applied to the track and operable by the station agent or other attendant to throw the same into position to trip the part on the train in case of oversight of the train operator to observe and give heed to the danger signal.

The invention consists of novel train devices and unique track or ramp appliances, both having the coöperating parts set centrally between the rails of the track so as to insure their positive and proper operation in either direction of travel of the train in an emergency or under abnormal conditions.

The invention further consists of the novel features and details of construction which hereinafter will be more particularly set forth, illustrated in the drawings here-to attached, and pointed out in the subjoined claims.

While the drawings illustrate the preferred embodiment of the invention, it is to be understood that in adapting the same to meet existing conditions, various changes in the form, proportion and minor details of construction may be resorted to without departing from the nature of the invention.

In the drawings,—

Figure 1 is a view in elevation of a locomotive engine and part of a track provided

with safety devices or automatic train control embodying the invention.

Fig. 2 is an enlarged transverse section on the line 2—2 of Fig. 1, looking to the right, as indicated by the arrow.

Fig. 3 is a detail section on the line 3—3 of Fig. 2, looking in the direction of the arrows.

Fig. 4 is a detail view of a portion of the train pipe showing the emergency valve and operating mechanism intimately associated therewith.

Fig. 5 is a detail sectional view of a box or casing containing an electric switch in the circuit for the magnet which operates the present device.

Corresponding and like parts are referred to in the following description and indicated in all the views of the drawings by the same reference characters.

The invention is illustrated in connection with a locomotive engine 1, although it is to be understood that the same is adapted to be applied in connection with a motor of any type.

The operating devices mounted upon the locomotive engine or other type of tractor or engine comprise a rock-shaft 2, an arm 3 at one end of the rock-shaft, and a lever 4, the latter being mounted midway of its ends, as indicated at 5. In the present instance, the usual saddle 6 forming one of the supports of the boiler likewise supports the mountings for the different parts. The rock-shaft 2 is mounted in brackets 7 which are attached to the saddle 6. The lever 4 is supported by brackets 8 which are likewise attached to the saddle 6. The lower end of the lever 4 is forked and provided with a roller 9 which is designed to reduce the frictional contact between the train and track coöperating devices to the smallest amount possible.

The train pipe 10 is provided in its length with the emergency valve 11 which is designed to perform the function of reducing the train pipe pressure for applying the brakes in the usual manner. The plug or movable part 12 of the emergency valve is provided with an arm 13 which is connected by means of a link 14 with an arm 15 at the outer end of the rock-shaft 2. Movement of

the rock-shaft 2 in either direction effects a corresponding movement of the arm 15 and movable part 12 of the valve, thereby resulting in a reduction of the train pipe pressure and an application of the brakes. In the normal position of the parts, the arms 13 and 15 and the link 14 are in vertical position; hence, movement of the rock shaft 2 in either direction results in actuation of the emergency valve in a manner to effect the desired result. This is plain on reference to Fig. 4, in which the full lines indicate the normal position of the parts and the dotted line positions of such parts when actuated in either direction.

The track operating device or ramp comprises oppositely-disposed bars or members 16 and 17. The members 16 and 17 are pivotally supported at their outer ends to suitable brackets 18 attached to cross ties or other convenient parts of the roadbed. The inner or meeting ends of the members 16 and 17 overlap and are connected in any manner. It is essential that the fastening 19 connecting the overlapping ends of the members 16 and 17 have a limited play, thereby preventing any impairment of the action of such members under the influence of the actuating means therefor. The members 16 and 17 are longitudinally disposed and are centrally located between the rails 20 comprising the track. The lever 4 is likewise centrally disposed. By this means, the automatic train control mechanism is adapted to be positively actuated in either direction of travel of the train without requiring any shifting or adjusting of the operating parts.

An arm 21 disposed transversely of the track is pivoted at one end, as indicated at 22, to a bracket 23 attached to a cross tie of the roadbed. The opposite end of the arm 21 is adapted to be connected with the actuating means, which, in the present instance, is shown as consisting of an electric device 24, which, in its specific formation, consists of a double-acting solenoid. A bell crank 25 disposed intermediate of the arm 21 and operating device 24 has one member connected to the free end of the arm 21, and a link 26 connects the other member of the bell crank to the core or armature of the magnet 24. When the magnet 24 is energized, its core or armature 27 is attracted, thereby operating the bell crank 25 and elevating the swinging end of the arm 21. The arm 21 is disposed to engage the members 16 and 17 at a point about opposite end pivot connection 19; hence, upward movement of the swinging end of the arm 21 elevates the opposing ends of the members 16 and 17, with the result that such members assume a position to incline in opposite directions, as indicated by the dotted lines in Fig. 3. In this position of the members 16 and 17, the

lever 4 will be tripped when the train or like part passes over the track devices represented by the members 16 and 17. The lever 4 will be operated no matter in which direction the train is moving. This is indicated by the dotted lines in Fig. 3. Movement of the lever 4 in either direction insures positive operation of the emergency valve, whereby the motive power is shut off and the brakes applied, thereby bringing the train to a standstill in the event of the engineer or train operator neglecting to give proper attention to the signal.

To insure positive operation of the arm 21 in its return to a normal position, a weight 28 is mounted thereon. Ordinarily, the weight of the arm 21 and parts associated therewith will be sufficient to restore such parts to normal position when the magnet 24 is devitalized by a shutting off of the current thereto. A keeper 29 is attached to one of the members and embraces the arm 21, thereby insuring harmony in the movement of the members 16, 17 and 21.

It is to be understood that the magnet 24 is adapted to be controlled from the usual semaphore or switch-stand, and inasmuch as the connecting means are unimportant and form no part of the present invention, it is not deemed necessary to illustrate or refer to the same in detail other than to state the manner of connection, whereby the magnet 24 is energized. When the signal is set, the circuit, not shown, including the magnet 24, is closed and such magnet becoming energized attracts its core 27 and operates the bell crank 25 and swings the free end of the arm 21 upward, thereby elevating the opposing ends of the pivoted members 16 and 17. Upon the approach of a train, motor car or like part, provided with complementary safety devices including the lever 4, the latter is tripped as it passes over the members 16 and 17, and through the intermediate connections hereinbefore described, actuates the valve 11 or like part and applies the brakes, thereby bringing the train to a stop in the event of oversight on the part of the engineer to give proper attention or heed to the signal displayed by the station master or other operator, tending to warn the engineer of impending danger so as to afford opportunity to bring the train to a stop or under control.

As best shown in Fig. 5 of the drawings, a switch 31 is included in the circuit which includes the magnet 24, and this switch is housed in a box or casing 30, having a suitable door 32 to give access to the switch, which door is provided with a suitable lock 33 to prevent unauthorized access to and operation of the switch. Normally, the switch 31 is closed, so that the device is under the control of the switch stand, semaphore or

the like. Under some conditions, it may be necessary to place two or more locomotives or trains in the same block, which can be accomplished by unlocking and opening the door 32 and opening the switch 31, whereby the circuit is opened and the magnet 24 de-energized, thus permitting the ramp members 16 and 17 to gravitate to an inoperative position, whereupon a locomotive can pass the 10 device without having its valve 11 actuated to stop the locomotive. Upon closing the switch 31, the circuit will be closed, the magnet 24 energized, and the ramp members 16 and 17 lifted into their operative position. 15 In the disposition of the parts, it has been found preferable to arrange the emergency valve 11 at a higher level than the compressor or main portion of the train pipe, thereby preventing any water of condensation 20 collecting in the valve and interfering with its positive and certain operation in an emergency.

Having thus described the invention, what I claim is:—

25 1. In automatic train control, an emergency valve, a rock-shaft, vertically-disposed arms extending from the rock-shaft and movable part of the emergency valve, a link connection between such arms, the arms 30 and link normally occupying a vertical position, and a vertically-disposed trip member having a connection with the rock-shaft for actuating the latter in either direction, said

trip member being fulcrumed between its ends. 35

2. In an automatic train control, an emergency valve, a rock-shaft provided with a pair of crank arms, a crank arm for the emergency valve, a link connecting the valve crank arm and one of the crank arms on the 40 rock-shaft and a vertically disposed trip member fulcrumed intermediate of its ends and provided with a slidable and pivotable connection with the other crank arm of the rock-shaft. 45

3. The combination with a locomotive having a saddle supporting the boiler, and the train pipe of an air brake system, of an emergency valve for the train pipe, a rock shaft mounted upon the saddle and disposed transversely beneath the boiler of the locomotive, crank arms upon the rock shaft, a crank arm for the emergency valve, a link connecting the valve crank arm and one of the crank arms on the rock shaft, and a vertically disposed trip member fulcrumed intermediate of its ends and provided with a slidable and pivotable connection with the other crank arm of the rock shaft. 50 55

In testimony whereof I affix my signature 60 in presence of two witnesses.

CHARLES W. WILSON.
